UNITED STATES PATENT OFFICE.

WILHELM SINGER, OF BERLIN, GERMANY.

FOLDING CARRIAGE.

SPECIFICATION forming part of Letters Patent No. 363,427, dated May 24, 1867.

Application filed September 30, 1886. Serial No. 214,923. (No model.) Patented in Germany January 11, 1885, No. 32,945.

To all whom it may concern:

Be it known that I, WILHELM SINGER, a subject of the King of Prussia, in the German Empire, and a resident of the city of Berlin, in the Kingdom of Prussia, Germany, have invented certain new and useful Improvements in Folding Carriages, of which the following is a specification.

The object of my invention is to procure a strong and ornamental child's carriage, which contracts and permits of its being folded when not in use. I attain this object in a manner illustrated in the accompanying drawings, of which—

15 Figure 1 is a side elevation of the child's carriage ready for use. Fig. 2 is an end view of Fig. 1. Fig. 3 is a side elevation of the child's carriage when folded.

The same letters refer to the same parts throughout.

I construct the carriage body of two parts, a and a' , hinged together at b . To the bottom of a are secured the ends of the springs c , which carry near their lower extremities the axle d , with the wheels f , and which aid to support the bottom of a' by means of the springs e , mounted upon c . To the bottom of a' are secured the springs e' , carrying below the bent axle d' , with the wheels f' , and serve to support the bottom of a .

The axle d' is bent upward to such an extent as to allow the small wheels f to pass between the larger wheels, f' , when the carriage is folded, thus forming a compact parcel.

When folded down, the two halves a and a' 35 of the carriage-body are braced by means of the braces h , one end of which is hinged to one part of the carriage-body, while the other is guided in a slide on the other part and held therein at the proper position by a suitable 40 clamping device.

Having described my invention, what I claim, and desire to secure by Letters Patent, is—

1. In a folding child's carriage, the combination of the body a a' with the springs c , e , 45 and e' , the axles d d' , wheels f f' , and braces h , as and for the purposes herein shown and described.

2. In a folding child's carriage, the bent axle d' , in combination with the spring c' , the axle 50 d , and wheels f , as and for the purposes herein shown and described.

Signed at Berlin, in the Kingdom of Prussia, this 10th day of September, A. D. 1886.

WILHELM SINGER.
